ROTARY TURRET SELECTOR

Donald H. Mitchell, Chicago, Ill., assignor to Galvin Manufacturing Corporation, Chicago, Ill., a corporation of Illinois

Application November 22, 1944, Serial No. 564,676

4 Claims. (Cl. 171—119)

1

This invention relates to a rotary turret for selectively connecting any one of a plurality of electrical circuit elements of like type but different constants in an electric circuit and particularly to a rotary turret selector of the multi-gang type. While the invention is of general application, it is particularly suitable for use as a selector to connect into the several stages of a high-frequency radio-frequency transmitter or receiver any of various frequency-determining circuit elements to adapt the apparatus to operate at any of a plurality of desired frequencies or frequency bands within a wide frequency range.

Heretofore there have been proposed rotary turrets for selectively connecting inductors, capacitors, resistors or other electrical circuit elements into an electrical circuit. Such devices have the well-known advantage that the lengths and the configurations of the lead-conductors to all of the several circuit elements, as selected, are exactly the same so that the electrical constants of the circuit with each of the selectable elements connected therein is precisely predetermined. Such an arrangement also facilitates the alignment of a plurality of stages of a multi-band radio-frequency signal-translating circuit including frequency-determining elements selected by such a turret selector.

However the rotary turret selectors of the prior art have been relatively complicated and costly in construction, particularly when constructed in multiple gangs. Among the factors contributing to such complexity and cost have been the accurate spacing and mounting of the rotary elements on the actuating shaft and the accurate alignment of the stationary elements or contacts with the rotary elements or contacts to ensure satisfactory performance. These factors have placed a definite limit on the number of turret elements which could be ganged together for unicontrol operation. The present invention is directed to a rotary turret selector in which either the stationary element or the rotary element is supported solely from the other element and is completely floating and self-aligning.

It is an object of the invention, therefore, to provide a new and improved rotary turret selector which avoids one or more of the above-named disadvantages of the prior art devices.

It is another object of the invention to provide a new and improved rotary turret selector which is simple and economical in construction and one which completely avoids the problem of alignment of the stationary and rotary elements.

It is still another object of the invention to

2

provide a new and improved rotary turret selector of the multi-gang type in which any desired number of turret elements may be ganged together for unicontrol while avoiding the problem of alignment.

- 5 In accordance with the invention, a rotary turret element for selectively connecting any one of a plurality of circuit elements of like type but different constants in an electric circuit comprises 10 an outer member or plate having a substantially circular aperture therein and a substantially circular inner member or plate disposed in the aperture, one of the members having a plurality of circuit elements distributed angularly thereon. 15 The turret also includes a plurality of radially extending means disposed about the adjoining periphery of one of the members and extending over opposed faces of the other of the members to retain the inner member within the aperture. 20 The turret also includes means for relatively rotating the inner and outer members and fixed and movable contact means including a pair of fixed terminals and effective upon relative rotation of the members selectively to connect the 25 circuit elements to the terminals.

In a preferred form of the invention, the rotary turret element for selectively connecting any of a plurality of circuit elements of the type described comprises a supporting plate having a substantially circular aperture therein, a substantially circular mounting plate disposed in the aperture and having a plurality of circuit elements distributed angularly thereon and having a central bore therein. The mounting plate is appreciably thicker than the supporting plate and has a diameter appreciably less than that of the aperture to provide a substantial clearance therebetween. The turret also includes a plurality of radially extending contact elements disposed 30 about the periphery of the mounting plate and individually connected to the circuit elements, the contact elements extending over opposite faces of the supporting plate and constituting the sole means for retaining the mounting plate 35 within the aperture. The turret also includes an actuating shaft extending through the bore of the mounting plate and keyed thereto, the diameter of the shaft being appreciably less than that of the bore to avoid restriction of movement of 40 the inner plate. A pair of terminal contacts is mounted on the supporting plate and is effective, upon relative rotation of the plates selectively to engage the contact elements associated with any 45 one of the circuit elements.

For a better understanding of the invention,

together with other and further objects thereof, reference is had to the following description taken in connection with the accompanying drawings while its scope will be pointed out in the appended claims.

Referring now to the drawings, Fig. 1 is a perspective view of a multi-gang rotary turret selector embodying the invention; Fig. 2 is a view in elevation of one of the rotary turret elements of the structure of Fig. 1; while Fig. 3 is a cross sectional detail through the cooperating contact along the line 3—3 of Fig. 2.

Referring now to Figs. 1 and 2 of the drawings, there is illustrated a gang rotary turret comprising a plurality of turret elements each adapted for selectively connecting any one of a plurality of electrical circuit elements of like type, such as inductors, capacitors, resistors, piezo-electric crystals, etc., but of different electrical constants in an electrical circuit. This turret comprises end frames 10 and 11 rigidly interconnected by means of through bolts or studs 12, each of which has disposed thereon a plurality of cylindrical spacers or washers 12a for spacing the several turret elements. The construction lends itself to ganging of any desired number of turret elements but by way of illustration there is shown a gang turret comprising nine turret elements as follows: The first turret element 13 in which the circuit elements selected are piezoelectric crystals 13a; the turrets 14, 15, 16, 17 and 18 in each of which the circuit elements selected are radio-frequency inductors 14a, 15a, 16a, 17a, and 18a, respectively; and the turret elements 19, 20 and 21 in which the circuit elements selected are radio frequency tuning capacitors 19a, 20a and 21a, respectively.

Each of the turret elements 13-21, insofar as the invention is concerned, are identical the differences comprising solely a question of detail in connection with the mounting and connection of circuit contacts of the several circuit elements in accordance with the physical characteristics of the elements. Therefore a detailed description of a single one of the turret elements is sufficient. To this end, there is illustrated in Fig. 2 in detail one of the turret elements, for example the element 14. This turret element comprises an outer stationary supporting plate 14b, having a substantially circular aperture 14c formed therein, and a substantially circular inner plate 14d disposed within the aperture 14c and having a central bore 14e. One of the plates 14b, 14d, preferably the latter, comprises a mounting plate having a plurality of circuit elements, in this case the inductors 14a, symmetrically distributed angularly thereon. Preferably, as illustrated, the inductor elements 14a are disposed radially on the mounting plate 14d and project somewhat beyond the outer periphery thereof. Each of the inductors 14a may be secured to the plate 14d in any suitable manner as by rivets or screws 14f engaging a portion of the inductor elements near the outer periphery of the mounting plate 14d and spring clips 14g engaging the inner ends of the several inductors 14a and secured to the plate 14d by pins or rivets 14h. The supporting plate has notches 14m in each of two or more corners, for example three as shown, for engaging the mounting bolts 12.

Preferably, the inner mounting plate 14d is appreciably thicker than the outer supporting plate 14b and has a diameter appreciably less than that of the aperture 14c in the mounting plate to provide a substantial clearance between

the plates 14b and 14d when the plate 14b is disposed within the aperture 14c.

Each of the turret elements also includes radially extending means disposed about the adjoining periphery of one of the plates, for example the mounting plate 14d, and extending over opposite faces of the other of the plates to retain the inner plate 14d within the aperture 14c, means for relatively rotating the inner and outer plates 14b and 14d, and fixed and movable contact means including a pair of fixed terminals and effective upon relative rotation of the plates selectively to connect the circuit elements to the fixed terminals. By the term "adjoining periphery" is meant either the inner periphery of the outer plate 14b or the outer periphery of the inner plate 14d, which two peripheries adjoin each other. Specifically in the preferred form of the invention, the radially extending retaining means comprises a plurality of radially extending tabs 14i disposed about the periphery of the inner mounting plate 14d, certain or all of these tabs constituting movable contact elements. For example, the tabs 14i on one side of the plate 14d constitute merely retaining tabs and those on the other side constitute contacts or, as shown, all of the tabs constitute contact elements individually connected in pairs to the several circuit elements or inductors 14a.

As more clearly shown in the cross-sectional detail of Fig. 3, the tabs or contact elements 14i extend over opposite faces of the supporting plate 14b, although, due to the fact that the mounting plate 14d is appreciably thicker than the supporting plate 14b, the contact elements 14i leave a gap or clearance 14j on one or both sides of the stationary supporting plate 14b. While as shown in Fig. 3, the inner plate 14d is physically appreciably thicker than outer plate 14b, a similar result may be obtained by appropriately offsetting the contact elements 14i so that plate 14d is functionally appreciably thicker than plate 14b and the term "appreciably thicker" is used herein in its generic sense to include these equivalent constructions. These tabs or contact elements constitute in part, or preferably as shown the sole, means for retaining the inner mounting plate 14d within the aperture 14c.

The turret described also includes means for relatively rotating the inner and outer plates of the several turret elements, specifically, an actuating shaft 22 common to all of the turret elements and extending through the bore of each of the inner mounting plates, such as the mounting plate 14d, and provided with a key-way 22a adapted to engage a key 14k projecting into the central bore 14e of the mounting plate 14d. The diameter of the shaft 22 is appreciably less than that of the bore 14e to provide a substantial clearance therebetween as shown.

Each of the turret elements also includes at least one and preferably a pair of fixed terminals such as terminals 23 mounted on supporting plate 14b and effective upon relative rotation of the plates 14b and 14d selectively to engage the pairs of contact elements associated with any one of the circuit elements or inductors 14a. On the other hand, if only a single fixed terminal contact 23 is provided, the other terminals of the several inductors 14a may be connected to a common terminal or slip ring through which the circuit to each of the inductors may be completed.

The actuating shaft 22 may be operated by any suitable mechanism, there being shown by way of example an operating shaft 24 coupled to the

shaft 22 through a worm 25 and worm gear 26 supported from the end frame 10.

It is believed that the operation of the rotary turret selector of the invention will be apparent from the foregoing description. In brief, actuation of the shaft 22 common to the several turret elements to rotate their respective inner mounting plates, such as the mounting plate 14d, is effective selectively to engage the pairs of contact elements 14i associated with the inductors 14a with the pair of fixed terminals 23 selectively to include any desired one of the circuit elements, such as the inductor 14a, into circuit therewith, it being understood that the fixed terminals 23 of each of the several turret elements is connected as desired to an external circuit. With this arrangement, it is seen that the lengths of the lead-conductors and their configurations remain the same as each of the circuit elements of a turret element is selectively and successively connected into circuit. The result is that the impedances external to the circuit elements themselves remain constant at predetermined values irrespective of which of the circuit elements is switched into position.

It will also be seen that, due to the clearance between the mounting plate 14b and the aperture 14c in the supporting plate 14b and due to the clearance 14f between the contact elements 14i and the supporting plate 14b, the mounting plate 14d is completely floating within the aperture 14c and is retained therein solely by contacts 14i which overlie opposed faces of the supporting plate 14b. At the same time, due to the clearance between the shaft 22 and the central bore 14e of the mounting plate 14d, the engagement between the shaft and the mounting plate is sufficiently loose that the shaft is effective merely to rotate the inner mounting plate 14d and otherwise does not restrict the movement of the plate 14d; that is, shaft 22 does not in any way support the mounting plate 14d which rests on or is supported by the supporting plate 14b only. As a result of this complete floating support of the mounting plate 14d, it is entirely self-aligning, that is, it naturally assumes a position such that its contact elements 14i are accurately engaged by the stationary contacts 23. This form of construction eliminates the requirement for accurate and rigid positioning of the mounting disks of the several turret elements on the common actuating shaft 22 and an accurate positioning of the supporting plates of the several turret elements by means of the bolts 12 and spacers 12a since the clearances described are ample to take care of any reasonable manufacturing inaccuracies.

While the invention has been described in connection with a rotary turret selector in which the circuit elements are mounted on an inner freely floating mounting plate surrounded by a supporting plate, it will be obvious to those skilled in the art that the invention is equally applicable to the converse arrangement in which the circuit elements are mounted on the surrounding plates and the terminal contacts on the inner plate. It will also be obvious that, if desired, the inner plates of the turret may be rigidly supported on the actuating shaft 14 and the outer plates given a free floating support from the frame of the device.

While there has been described what is at present considered to be the preferred embodiment of the invention, it will be apparent to those skilled in the art that various changes and modifications may be made therein without departing from the spirit or scope of the invention.

I claim:

1. A rotary turret element for selectively connecting any one of a plurality of electrical impedance elements of like type but different constants in an electric circuit comprising, an outer plate having a substantially circular aperture therein, a substantially circular inner plate disposed in said aperture, one of said plates having a plurality of said impedance elements distributed angularly thereon, one of said plates being appreciably thicker than the other and said inner plate having a diameter appreciably less than that of said aperture to provide a substantial clearance therebetween, radially extending means disposed about the adjoining periphery of said one of said plates and extending over opposite faces of the other of said plates to retain said inner plate loosely within said aperture, means for relatively rotating said inner and outer plates, and fixed and movable contact means including a pair of fixed terminals and effective upon relative rotation of said plates selectively to connect said impedance elements to said terminals.
2. A rotary turret element for selectively connecting any one of a plurality of electrical impedance elements of like type but different constants in an electric circuit comprising, an outer plate having a substantially circular aperture therein, a substantially circular inner plate disposed in said aperture, one of said plates having a plurality of said impedance elements distributed angularly thereon, a plurality of radially extending contact elements disposed about the adjoining periphery of said one of said plates and individually connected to said impedance elements, means including said contact elements for retaining said inner plate within said aperture, means for relatively rotating said inner and outer plates, and at least one terminal contact effective upon relative rotation of said plates selectively to engage said contact element associated with any one of said impedance elements.
3. A rotary turret element for selectively connecting any one of a plurality of electrical impedance elements of like type but different constants in an electric circuit comprising, a stationary supporting plate having a substantially circular opening therein, a substantially circular inner plate disposed loosely in said aperture and having a central bore therein, one of said plates having a plurality of said impedance elements distributed angularly thereon, radially extending means disposed about the adjoining periphery of one of said plates and extending over opposite faces of the other of said plates to retain said inner plate within said aperture, an actuating shaft extending through said bore of said inner plate and keyed thereto, the diameter of said shaft being appreciably less than that of said bore to avoid restriction of movement of said inner plate, whereby said inner plate is freely floating in said opening, and fixed and movable contact means including a pair of fixed terminals and effective upon relative rotation of said plates selectively to connect said impedance elements to said terminals.
4. A rotary turret element for selectively connecting any one of a plurality of impedance elements of like type but different constants in an electric circuit comprising, a supporting plate having a substantially circular aperture therein, a substantially circular mounting plate disposed in said aperture and having a plurality

of said impedance elements distributed angularly thereon and having a central bore therein, said mounting plate being appreciably thicker than said supporting plate and having a diameter appreciably less than that of said aperture to provide a substantial clearance therebetween, a plurality of radially extending contact elements disposed about the periphery of said mounting plate and individually connected to said impedance elements, said contact elements extending over opposite faces of the supporting plate and constituting the sole means for retaining said mounting plate within said aperture, an actuating shaft extending through the bore of said mounting plate and keyed thereto, the diameter of said shaft being appreciably less than that of said bore to avoid restriction

of movement of said inner plate, and a pair of terminal contacts mounted on said supporting plate and effective upon relative rotation of said plates selectively to engage the contact elements associated with any one of said impedance elements.
